FIG. III.

FIG. VI.

FIG. V.

FIG. VII.

Inventor:

RUSSELL SCOTT ELLIS,

By *Arthur E. Haig*,
Attorney.

UNITED STATES PATENT OFFICE.

RUSSELL SCOTT ELLIS, OF PHILADELPHIA, PENNSYLVANIA.

CONCRETE STRUCTURE.

Application filed December 21, 1923. Serial No. 681,972.

My improvements may be advantageously employed in the construction and arrangement of bulk heads, piers and similar structures, and is particularly adapted for installing such structures in sandy soil.

As hereinafter described, my invention includes the provision of concrete members having metallic reinforcements extending therethrough, adapted to serve as conduits for water to displace the soil in which such members are to be implanted, and also as conduits for concrete in a mobile state to form foundations at the base of such members, after they are implanted; also concrete members adapted for use in conjunction with the tubular conduit members aforesaid to form barriers such as may be utilized as bulk heads and similar walls.

My invention includes the various novel features of construction and arrangement and method of procedure hereinafter more definitely specified. However, said method of procedure is the subject matter of my copending divisional application Serial No. 725,567 filed July 12, 1924, for Letters Patent of the United States for improvement in methods of sinking concrete structures by means of water jetting.

In the drawings; Fig. I is a front elevation of a bulk head embodying my improvements, erected in sandy soil, as seen from the right hand side of Fig. II.

Fig. II is a vertical sectional view, taken on the line II, II in Fig. I and in the direction of the arrows on said line.

Fig. III is a perspective view of one of the top slabs shown in Figs. I and II.

Fig. IV is a perspective view of one of the lower slabs shown in Figs. I and II.

Fig. V is a diagrammatic view, partly in elevation and partly in section at right angles to the plane of Fig. II, showing one of the vertical tubular columns of the structure shown in Figs. I and II, in course of installation, in accordance with my method.

Fig. VI is a fragmentary vertical sectional view, on a larger scale than the other figures, showing a joint in a tubular column conduit formed of axially aligned separable sections.

Fig. VII is a perspective view of one of the slotted bolts 19 indicated in Figs. I and II.

Referring to the form of my invention

shown in Figs. I and II; a series of vertical tubular columns 1 are installed, in parallel relation, in the sandy subsoil 2 so as to form a bulk head to protect the top soil 3 from the encroachment of the sea or other body of water 4. Each of said columns 1 is a substantially cylindrical body of concrete, having an axial tubular metal core 6, conveniently formed of an iron or steel pipe screw threaded at each end and provided at its upper end with a screw coupling 7 to engage a pipe of similar size, for the purpose of effecting the installation of said column, as hereinafter described.

Said column has the step 8 formed of concrete, projecting from but one side thereof, in unitary relation therewith, and preferably reinforced by the metal member 9 to determine the position and support the bottom one of the series of substantially plane slabs 10 which are each conveniently of the form indicated in Fig. IV. Each of said slabs 10 comprises a substantially plane rectangular body having a flat face upon its front side and a rib 11 upon its rear side and substantially semicylindrical notches 12 at its respectively opposite ends. Said lower slabs 10 are surmounted by upper slabs 14, each conveniently formed as shown in Fig. III and comprising a substantially plane body with a top flange 15 extending at right angles thereto and overhanging the columns local to said flange and serving to close the openings in the tops of said columns and the cores therein; said body having a plane front face but having its rear face reinforced by a rib 16 similar to the ribs 11 aforesaid. Said top flange 15 is also preferably reinforced by a similar rib 17, pendent from the under side thereof.

I find it convenient to detachably connect said columns 1 with said slabs 10 and 14 by providing each of said columns with a vertical series of bolts 19 which are imbedded therein so as to project at right angles to the axis thereof, as indicated in Fig. II. Each of said bolts has a slot 19^a extending vertically through it at its outer end to receive a wedge 20. Said bolts are adapted to extend between adjoining slabs in the notches 12 at the ends of the latter and, when the slabs are assembled in the position shown in Fig. II; washers 21 are placed upon said bolts so as to overlap adjoining slabs and

the latter secured by driving the wedges 20 into the position shown in Fig. II. It may be observed that the notches 12 in the ends of the adjoining slabs 10 and 14 are complementary; so that each of said bolts 19 suffices to engage the adjoining ends of two of said slabs and relative displacement thereof is prevented by the single washer 21 and wedge 20 connected with the respective bolt.

As indicated at the left in Fig. I; the columns 1 may be installed in the sandy soil 2 without any foundation. However, as shown at the right in Fig. I and also in Fig. II; each of said columns may be provided with a concrete foundation 23 which may be formed after the installation of the column as hereinafter described. Such foundations 23 of course render it more difficult to remove the columns 1. Therefore, if the bulk head is designed for temporary use, such foundations are omitted. Of course, the structure assembled as above described and illustrated in Fig. II may be taken apart by removing said wedges 20 and slabs 10 and 14 and withdrawing said columns, without impairing any part of the structure which may be used again.

As indicated in Fig. V; the column 1 may be conveniently sunk in the soil 2 by connecting with its top coupling 7 the nozzle 25 of the flexible conduit 26 through which water 27 may be conveyed to said column and driven downwardly therethrough under pressure while said column is suspended by any convenient overhead tackle. For instance, a cable 28 extending from the eye 29 on said nozzle serves to support said column 1 in vertically pendent position so that it may be permitted to gravitate into the pit 30 being formed by the water 27 flowing downwardly through the tubular reinforcement 6 of said column 1 and thence upward around said column to the surface 31.

Although I have shown said columns 1 unitary from end to end thereof; it is to be understood that they may be formed in sections as indicated at 1^a and 1^b in Fig. VI.

The construction and arrangement above described are such that water under pressure may be driven downwardly through the axial tubular conduit 6 of the column 1 or the column formed of sections 1^a and 1^b, or any other suitable structural element to sink the same into the soil to the desired depth by washing the soil from beneath it and permitting it to gravitate. Thereafter, the water may be shut off from said nozzle 25 at the valve 50, and the valve 68 be opened to discharge concrete, from the flexible conduit 67, through said conduit 6 to form a foundation 23 at the bottom thereof.

However, I do not desire to limit myself to the precise details of construction, arrangement and method of procedure herein set forth, as it is obvious that various modi-

fications may be made therein without departing from the essential features of my invention, as defined in the appended claims.

I claim:

1. In a concrete structure, the combination with a plurality of vertical columns, each comprising a tubular body of concrete and a tubular metallic core extending through said concrete and projecting at the bottom thereof, and said core being provided with internal screw threads at the top thereof extending entirely within the top of said concrete body; each column having a laterally projecting step, and a vertical series of bolts set in the concrete portion thereof and extending transversely to the axis thereof, in spaced relation, above said step, and each bolt having means arranged to engage a wedge; of a series of slabs, each comprising a substantially rectangular body with bolt notches at opposite ends thereof adapted to engage the bolts on said columns; the notches in the ends of adjacent slabs being complementary; the top slabs having transverse flanges overhanging said columns, closing the upper ends of said tubular metallic cores and protecting said threads; each of said slabs having a reinforcing rib extending horizontally, intermediate of its width; washers engaging said bolts and overlapping the ends of the adjoining slabs, upon opposite sides of said bolts; and wedges engaging said bolts and bearing against said washers; whereby each of said bolts suffices to engage the adjoining ends of two of said slabs, and said slabs may be released by lateral movement of said wedges.

2. In a concrete structure, the combination with a plurality of vertical columns each comprising a tubular body of concrete and a tubular metallic core provided with internal screw threads extending entirely within the top thereof; each column having a laterally projecting step, and a vertical series of bolts set in the concrete portion thereof and extending transversely to the axis thereof, in spaced relation, above said step; of a series of slabs each comprising a substantially rectangular body with bolt notches at opposite ends thereof adapted to engage the bolts on said columns; the notches in the ends of adjacent slabs being complementary; the top slabs having means overhanging said columns and closing the upper ends of said tubular metallic cores; each of said slabs having a reinforcing rib extending horizontally, intermediate of its width; washers engaging said bolts and overlapping the ends of the adjoining slabs, upon each side thereof; and means engaging said bolts and bearing against said washers; whereby each of said bolts suffices to engage the adjoining ends of two of said slabs.

3. In a concrete structure, the combina-

tion with a plurality of vertical columns each comprising a tubular body of concrete and a tubular metallic core provided with internal screw threads extending entirely within the top thereof; each column having a laterally projecting step, and a vertical series of bolts set in the concrete portion thereof and extending transversely to the axis thereof, in spaced relation, above said step; the heads of said bolts being imbedded in the concrete between said core and the outer surface of the column through which said bolts extend; of a series of slabs each comprising a substantially rectangular body with bolt notches at opposite ends thereof adapted to engage the bolts on said columns; the notches in the ends of adjacent slabs being complementary; washers engaging said bolts and overlapping the ends of the adjoining slabs, upon each side thereof; and means engaging said bolts and bearing against said washers; whereby each of said bolts suffices to engage the adjoining ends of two of said slabs.

25 4. In a concrete structure, the combination with a plurality of vertical columns each comprising a tubular body of concrete and a tubular metallic core extending therethrough; each column having a laterally projecting step, and a bolt set in the concrete portion thereof and extending transversely to the axis thereof, in spaced relation, above said step, and each bolt having a laterally projecting head between said core and the outer surface of said column, and exterior means arranged to engage a wedge; of a series of slabs each comprising a substantially rectangular body with bolt notches at opposite ends thereof adapted to engage the bolts on said columns and resting on said steps; the notches in the ends of adjacent slabs being complementary; washers engaging said bolts and overlapping the ends of the adjoining slabs, upon each side thereof; and wedges engaging said bolts and bearing against said washers; whereby each of said bolts suffices to engage the adjoining ends of two of said slabs.

50 5. In a concrete structure, the combination with a plurality of vertical columns each comprising an open tubular body of concrete; each column having a laterally projecting step, and a bolt set in the concrete portion thereof and extending transversely to the axis thereof, in spaced relation, above said step; of a series of slabs each comprising a substantially rectangular body with bolt notches at opposite ends thereof adapted to engage the bolts on said columns; the notches in the ends of adjacent slabs being complementary; the top

slabs having means overhanging said columns and closing the upper ends thereof; washers engaging said bolts and overlapping the ends of the adjoining slabs, upon each side thereof; and means engaging said bolts and bearing against said washers; whereby each of said bolts suffices to engage the adjoining ends of two of said slabs.

65 6. A wall comprising a series of precast concrete columns set in vertical parallel spaced relation and each having a series of bolts imbedded therein and projecting therefrom at right angles to the plane of the series of columns said bolts having laterally projecting heads imbedded in and concealed by the concrete intermediate of the width of said columns; a series of slabs each comprising a substantially rectangular body with bolt notches at opposite ends thereof adapted to engage the bolts of said columns; the notches in the ends of adjacent slabs being complementary; washers on said bolts overlapping the ends of the adjoining slabs, upon each side thereof; and means engaging said bolts and bearing against said washers; whereby each of said bolts suffices to engage the adjoining ends of two of said slabs.

70 7. A concrete wall unit comprising a substantially rectangular slab having similar bolt notches in each end thereof; whereby the notches in adjoining ends of a series of such slabs are complementary and afford bolt openings, between adjoining slabs assembled in the same plane; and means reinforcing said slab between said notches, exterior to said plane.

75 8. A wall unit, such as described in claim 7; having a rib projecting from one face thereof, in alinement with the notches in the respectively opposite ends thereof; whereby said unit is reinforced at said notches against lateral stresses tending to crack it.

80 9. A concrete wall unit comprising a substantially rectangular slab having similar bolt notches in each end thereof; whereby the notches in adjoining ends of a series of such slabs are complementary and afford bolt openings, between adjoining slabs assembled in the same plane; and having a horizontal flange projecting at right angles to the plane thereof at the top thereof, and a reinforcing rib pendent from the under side of said top flange, in spaced relation with the adjacent face of the slab; said pendent rib terminating short of the opposite ends of said slab.

85 10. In testimony whereof, I have hereunto signed my name at Philadelphia, Pennsylvania, this 18th day of December, 1923.

RUSSELL SCOTT ELLIS.
